LEONARD L. HODGES, OF BOSTON, MASSACHUSETTS.

Letters Patent No. 73,808, dated January 28, 1868.

PICTURE-FRAME SUPPORTER.

The Schedule referred to in these Letters Patent and making part of the same.

TO ALL PERSONS TO WHOM THESE PRESENTS MAY COME:

Be it known that I, LEONARD L. HODGES, of Boston, in the county of Suffolk, and State of Massachusetts, have made a new and useful Invention for Supporting a Picture-Frame when suspended from a hook or its equivalent; and I do hereby declare the same to be fully described in the following specification, and represented in the accompanying drawings, of which—

Figure 1 denotes a rear view, and

Figure 2 a side view of a picture-frame with my invention applied to it.

Figure 3 is a vertical section, taken through one of the catch-racks.

In carrying out my invention, I apply and fasten to the rear side of a picture-frame, A, (see the drawings,) what I term two catch-racks, B B, they being arranged on the frame in manner as represented in figs. 1 and 2. A transverse section of one of such racks is shown in Figure 4, it being composed of a piece of metal, channelled on its rear side, and lengthwise thereof, and having a series of holes, a a a, arranged in it, in manner as shown in the drawings. At its extremities the rack has ears, b b, to receive screws c c, by which the rack is secured to the picture-frame. To each of the ends of the cord C, for suspending the picture-frame, I affix a hook, D, or hooked wire formed with a bulb, d, at one end, and an eye, e, at the other, the said eye being to receive the cord, which, after being passed through the eye, is to be knotted, as shown at f.

Figure 5 is a side view of the hooks or catches D.

Each of the apertures of the catch-rack is formed by an elongated slot, crossing a round hole having a diameter greater than the width of the slot, such diameter being a little greater than that of the bulb of the catch. The slot has a width about equal to or a little greater than the diameter of the shank of the catch near the bulb. The catch, after the introduction of its bulb into any hole of the catch-rack, will take into the cross-groove of such hole, and by such and the bulb, will be connected to the rack. Thus, by means of the catches and the racks connected with the cord, the picture-frame may be supported and adjusted to any desirable height, the adjustment being effected by changing one of the catches into some other hole of the rack. The catch-racks and hooks enable the slope of a picture-frame, or its inclination with respect to a wall, to be modified or changed as circumstances may require, and thus they are of great advantage in hanging pictures, or other articles of like character.

What I claim as my invention, is—

The combination of the catches and catch-racks with the suspension-cord and picture-frame, the whole being substantially as described.

LEON'D L. HODGES.
